(57) CLAIM

The ornamental design for a battery housing, as shown and described.

DESCRIPTION

FIG. 1 is a front, right, bottom isometric view of a battery housing showing our new design;

FIG. 2 is a front elevational view thereof;

FIG. 3 is a right side elevational view thereof, the left side being a mirror image;

FIG. 4 is a top plan view thereof;

FIG. 5 is a bottom plan view thereof; and,

FIG. 6 is a rear elevational view.

The broken lines shown in FIG. 6 enclose an area that forms no part of the claimed design.
